UNITED STATES PATENT OFFICE

92,818

DESIGN FOR A CONTAINER FOR MOLDED ICE CREAM

Elmer J. Mather, Chevy Chase, Md.

Application March 21, 1934, Serial No. 51,123

Term of patent 14 years

To all whom it may concern:

Be it known that I, ELMER J. MATHER, a citizen of the United States of America, and a resident of Chevy Chase, Maryland, have invented a new, original, and ornamental Design for a Container for Molded Ice Cream, of which the following is a specification, reference being had to the accompanying drawing, forming part thereof, in which drawing Fig. 1 is a perspective view and

Fig. 2 is a front view of a container for molded ice cream embodying my new design.

I claim:

The ornamental design for a container for molded ice cream as shown.

In testimony whereof I have signed this specification.

ELMER J. MATHER.
